DATING DEVICE

William J. Pearson, Los Angeles, Calif.

Application October 23, 1931, Serial No. 570,628

4 Claims. (Cl. 101—287)

This invention relates to improvements in dating devices designed to be used in conjunction with the numeral printer in a parcel post machine, such as is disclosed in my co-pending application Serial No. 367,106, filed by me May 29, 1929, for Parcel post weighing and stamp printing machine, which is designed to weigh parcel post packages and to print parcel post stamps of the prepaid metered type.

10 The parcel post weighing and stamp printing machine disclosed in said application is designed for printing purposes, more particularly the printing of metered parcel post stamps, wherein it may be required to print a stamp providing 15 the name of the place of original mailing, the date, the zone number to which the package is addressed, the weight of the package in pounds, the monetary value of the stamp derived from the weight and the zone, a serial number, and such 20 other words, phrases, figures, decorations, and designations as it may be desired to print. This mechanism is used in conjunction with a scale, meters, and a paper supply, and may be motor driven and used for any printing.

25 This machine is particularly adapted for the printing of parcel post stamps upon a paper strip which is delivered from a machine, cut to the proper stamp length and, being gummed on the reverse side, may be moistened at the delivery 30 point of the machine, and in this condition attached to the package to be mailed. There may be printed a duplicate stamp that may be wound upon a spindle within the machine, or delivered in cut lengths with the stamp.

35 This machine also provides a novel method of setting up within the machine the mechanical equivalent of a set of numbers put into the machine by an operator by actuation of the keys of the keyboard; when the required numbers have 40 been set up, or the required number of keys operated on the keyboard, by means of a control key and the connected motor drive, the machine operates to print a stamp, and at the completion of the printing operation, the machine is cleared 45 and prepared for the next operation.

The machine includes a total registering meter and a reset meter, a meter actuating mechanism which is set up by the keyboard with mechanical equivalents of the numbers punched in by 50 the keys of the keyboard and a numeral printing mechanism which is also operated from the keyboard to set up the numbers punched in on the keys.

55 My invention provides a novel means for printing the date upon a parcel post stamp or the

like; more particularly the invention relates to a removable dater device comprising a removable member containing separate type which may be removed and changed as desired.

An object of my invention is to provide a dater 5 wherein the type may be changed from day to day, as required to keep the date to be printed current with the day, month and year, and which is readily accessible, removable and replaceable within the machine.

10 An object of my invention is to provide a dater device which, when removed from the machine, will cause the supply of current to the motor to be cut off, and, when improperly replaced in the machine, will continue to break the current circuit and only upon proper adjustment within the receiving area and upon alignment with the other printing members of the printer will the circuit be reconnected and the machine made operable.

15 Another object of my invention is to provide 20 a dating device with type faces aligned with the other printing faces adjoining it and which may be inked by the same inking device by which the other printing faces are inked.

25 Another object of my invention is to provide a 30 dating device wherein there are removable type of similar size and character, but which are provided with angular portions on their outer surfaces, whereby type may be placed in the receiving aperture of the dater only in an established relation and whereby it would be impossible to make an incorrect set-up of the dater type, for example, placing the year type where the month type should be.

35 Various other objects and advantages will be 40 more fully apparent from the following description of the accompanying drawings which form a part of this disclosure, and which illustrate a preferred form of embodiment of the invention.

Of the drawings:

45 Fig. 1 is an elevation of the numeral printer containing the dating device, the ribbon carrier, the keyboard unit and the moistener.

Fig. 2 is an elevation of the printer unit containing the moistener, taken from the left of the illustration of the printer disclosed in Fig. 1 and showing the electric switch and motor (diagrammatically), but omitting the showing of the ribbon rewind.

50 Fig. 3 is a sectional elevational view of the 55 printer unit shown in Fig. 1 taken opposite to Fig. 2 and showing in section the dater device and the type contained therein in non-printing position.

Fig. 4 is a view of a portion of the printer in

section similar to Fig. 3 but showing the printer in printing position.

Fig. 5 is a plan view of the dating device partly in section and somewhat enlarged, showing the relative positions of the switch, positioning pin and the dater type, and,

Fig. 6 is an enlarged view in section of the front section of the printer including the dating device and the platen in non-printing position, taken approximately on line 3—3 of Fig. 1.

Fig. 7 is a detail view of the printer drive cam, taken in a direction opposite to that of Fig. 6.

Fig. 8 is a detail elevational view from the opposite side of the machine from Fig. 2, showing the connections from the cam shaft for operating the printing hammer and the power drive shaft which is driven by the motor of the machine.

The numeral printer A comprises the dater device B, the ribbon rewind C, the keyboard D, the moistener E, and the duplicate stamp spindle F, which are parts of a parcel post machine wherein the dating device is used.

The dater proper comprises a removable block 10 provided with a knurled handle 11 and having a recess 12 designed to receive the dating type 13, 14 and 15. The wall of the recess 12 is provided with angular surfaces, an angle offset on one side comprising an offset 16 which constitutes a key adapted to be contacted by a corresponding keyway 17 in the type blocks 13, a second off-set 18 constituting a key which is fitted by a keyway 19 in the type blocks 14, and a third off-set 20 constituting a key which is fitted with a corresponding keyway 21 in the type blocks 15, thus providing means to allow only the type designed to fit in each portion of the recess 12 to enter. For retaining the type in vertical position when placed in the dater block 10 I have provided an off-set or shoulder 22 in the dater block 10 and a corresponding shoulder 23 in each of the type blocks 13, 14 and 15. Thus, as the type is assembled into the dater block, it is set down against the shoulder 22, bringing it into alignment with the other printing faces of the numeral printer.

The dater block 10 is removably mounted in a carriage 24, which is an integral part of the numeral printer and operates with a reciprocal vertical movement in guides 25 supported by a printer frame 26.

The printer A comprises type wheels 28 rotatably mounted upon a shaft 27 (comprising the main part of the numeral printer) and an automatic serial numbering printer 29, also assembled on the shaft 27; the shaft 27 is secured at one end in the dater carriage 24 and has its other end secured in a member 30 slidable vertically with a reciprocal movement on guides (not shown) similar to the guides 25; thus there is provided a means for printing a stamp wherein the date type are in alignment with the other type faces and are operated simultaneously with them.

For the purpose of inking the several type faces in the numeral printer A, I have provided an ink reservoir 31 with a filler tube 32, the reservoir 31 having an absorbent surface comprising the fabric 33; for distributing the ink from the reservoir 31 to the various type faces I have provided a felt roller 34 mounted in a carriage 35 which travels in the track 36 with a lateral movement to and from the reservoir 31 to the type faces. In Fig. 3 the type 13, 14 and 15 are shown in non-printing position, this being the position in which they

are inked preparatory to a printing operation by the roller 34; the roller 34 is operated from a source of power and by means not shown.

To operate the type members of the printer A to print a stamp and to give to the type members a hammer-like movement which is required by this particular form of construction of parcel post machine, I have provided a spring hammer 37 mounted on rocking arms 38 pivoted on rock shaft 39 driven by a motor (not shown) and tensioned by a set of springs 40; this hammer, in its operation is raised and then tripped by a cam 67 on shaft 66, driven by a motor R the end 70 of a lever 71 on shaft 39 engaging the cam face 68 for this purpose; the two positions of the hammer and the dater device are best illustrated in Figs. 3 and 4, Fig. 3 showing the mechanism in non-printing position, and Fig. 4 showing it in printing position.

The shaft 66 is gear-connected by gears 65a and 64a (Fig. 8) with shaft 163 which in turn is connected by bevel gearing 63a with power drive shaft 162 which is driven through suitable connections, as for example, belt S from the motor R, located in a different part of the machine, but illustrated more or less diagrammatically in Fig. 2.

For locating the dater block properly in the carriage 24 so that the type members 13, 14 and 15 will be in proper alignment with the other printing surfaces, I have provided a locating pin 41 which enters a dwell 42 in the dater block 10 when properly located; an extension 43 of pin 41 has a pin 44 entering a slotted opening 45 in the switch lever 46, which is pivotally mounted at 47 to the side of the casing 26. A switch-operating member 48 on one end of lever 46 is provided for the purpose of opening and closing the electric circuit to a motor, (not shown), which comprises the power drive means for rock shaft 39 of the printer A and for the other elements of the parcel post machine; the switch comprises two contacting members 49 and 50; the other end of the switch lever 46 is provided with a knurled handle 51 for manual operation to remove the locating pin 41 from the dwell 42 and allow the dater block 10 to be removed from the carriage 24 for the purpose of changing the type. An additional function of the locating pin 41 is to lock the dater block 10 in position once it has entered the dwell 42. The hammer 37 contacting directly against the upper plate 65 of the carriage 24, and the plate contacting the upper surfaces of the type 13, 14, and 15, the construction causes proper horizontal alignment of the dater type with the type faces of the numeral wheels mounted within the printer. The dater block 10, which is slidably mounted in the carriage 24, is supported at the sides by the contacting surfaces of the carriage 24 and at the bottom by extended portions of the carriage 24 comprising the tracks 52.

Fig. 5 shows three positions of the switch arm 46. In the normal position, shown in solid lines, the dater block 10 is properly located within the carriage 24 and the locating pin 41 is properly seated in the dwell 42; the broken lines 53 illustrate the position to which the parts are moved by manual operation for the purpose of removing the dater block 10; the broken lines 54 illustrate the position of the pin 41 and the arm 46 when the dater block 10 has been removed. Movement of arm 46 in either direction operates through the switch-operating member 48, to move one or the other of the contact members 49 or 50, according to the direction of the movement, thus breaking the

motor circuit and preventing operation of the printer for printing purposes either when the dater block 10 is removed or when it is in an incorrect position in the carriage 24.

5 The parcel post machine herein referred to is designed to use a paper tape for the purpose of printing parcel post stamps and a second paper tape for receiving a duplicate copy print of each stamp as printed in the machine; the duplicate paper tape 55 (Fig. 1) is shown being wound upon the spindle F. The paper tape 56 used for printing a stamp is illustrated by broken lines which indicate the position assumed by a stamp after it has been printed and forwarded into the moistener E and severed from the balance of the paper tape by the knife 57. The two paper tapes pass through a guide plate 58, wherein they are separated, the inked ribbon 59 being allowed to travel between the two tapes for the purpose of making 10 a print on the duplicate tape at the time that the postage stamp is printed. For the purpose of providing a surface against which the printer will operate, and to properly support the two paper tapes for printing purposes, I have provided a 15 platen 60 of semi-resilient material mounted in a support in the form of an anvil 61 which is assembled as a part of the ribbon device C. The ribbon 59 is secured to two spindles 62 and 63, upon 20 which it is wound alternately by the winding mechanism 64, which incorporates reversing elements operated by power means (not shown).

The operation of setting the type in the dater block 10 is accomplished by removing the pin 41 from the dwell 42 by means of the handle 51 on 25 arm 46 (Fig. 1) to release the dater block 10, and removing the block from the carriage 24 by means of the handle 11. By merely turning the block 10 over the type can be dropped out freely, whereupon the proper date blocks may be selected and placed 30 in the dater block 10; the dater, as designed in this machine, has the month, day and year, each upon separate type blocks; and as shown in Fig. 5 the type block 15 would preferably carry the month, the type block 14 the day of the month, 35 and the type block 13 the year; to assist the operator in re-setting the type the recited keyways 17, 19, and 21 are provided in each type block for the purpose of making the proper selection of type easier and quicker, and for preventing the 40 otherwise possible wrong assembly of the type.

When the type is re-set the dater block 10 is ready to be replaced in the carriage 24; the operator then, by means of the handle 51, removes the locating pin 41 from the path of the dater block 45 10, slides the dater block 10 into the carriage 24 and releases the spring tensioned handle 51, thus allowing the locating pin 41 to find and enter the dwell 42 upon the proper positioning of the dater block 10 within the carriage 24; the proper seating 50 of pin 41 permits the switch contacts 49 and 50 to be closed, placing the motor circuit through wires 98, 99 in condition for the next printing operation.

The structure of the dater device itself, the removing and replacing means, the locking and releasing means, the connected switch, and the other parts disclosed, may be varied in form without departure from my invention, as hereinafter

claimed; the disclosure of this description and drawings are merely an illustration of one embodiment of my invention, which is susceptible of embodiment in various forms, all coming within the scope of the claims which follow.

I claim:

1. In a printing device for parcel post machines and the like, independent printing elements, one element being movable relative to another element, means adapted to actuate said printing elements to produce a printing operation, and an electrical control preventing operation of the said last means until said printing elements are aligned 10 said control comprising an electrical switch, a switch actuating member, a recess in said movable element, and a pin connected to said member and seated in the recess in said movable element when said elements are aligned.

2. In a printing device for parcel post meter machines and the like, a pair of independent 20 printing elements, one of said printing elements being movable relative to the other printing element, an electrical switch means for actuating both said printing elements to produce printing engagement upon work, electrical connections between said switch and last named means and means for actuating said switch to prevent the operation of the device when the movable printing element is not aligned with the other element, said means comprising a recess in said movable 25 element, a spring-pressed pin seated in said recess when said movable element is aligned, and an arm connected to said pin for actuating said switch.

3. In a printing device, a plurality of independent printing elements, a support for said elements, one of said elements having a recess and being removable from said support, a motor for actuating said printing elements, an electrical switch controlling said motor, a control member 30 for actuating said switch for preventing actuation of the printing elements by said motor when said movable element is removed from said support or is not aligned with the other printing elements, a pin carried by said control member and adapted 35 to seat in said recess when the movable element is on said support and aligned with the other printing elements.

4. In a printing device, a supporting frame, a shaft supported in said frame, means for actuating said shaft, a switch controlling said shaft actuating means, printing wheels on said shaft, a printing element removably positioned in said frame and normally in alignment with said printing wheels, said printing element having a recess 50 in its surface and said frame having an opening registering with said recess when said printing element is positioned in said frame in alignment with said printing wheels, a control arm pivotally mounted on said frame for actuating said switch, 55 said control arm having a pin thereon projecting through said opening into said recess when said printing element is properly positioned in said frame and adapted to prevent the operation of the device when said printing element is removed 60 from said frame or is not in alignment with said printing wheels.

WILLIAM J. PEARSON.
